(57) **CLAIM**

The ornamental design for automobile LED headlight, as shown and described.

DESCRIPTION

FIG. 1 is a top view of the automobile LED headlight design; FIG. 2 is a bottom view thereof; FIG. 3 is a front view thereof; FIG. 4 is a back view thereof; FIG. 5 is a right-side view thereof; FIG. 6 is a left-side view thereof; FIG. 7 is a top-side vertical view thereof; and, FIG. 8 is a bottom-side vertical view thereof.

The automobile LED headlight design is a LED headlight suitable for all automobile models with 7-inch square mounting position. The design is a full LED light source design, with four core optics forming a standard high beam and low beam light system. The left and right curved optics are parking lamps. The design is energy saving, beautiful and reliable, making driving safer.
